UNITED STATES PATENT OFFICE.

DAVID PETRI-PALMEDO, DECEASED; BY ANNA EMILIE EMMA PETRI-PALMEDO, EXECUTRIX, OF BERLIN-CHARLOTTENBURG, GERMANY, ASSIGNOR TO STANDARD COMPOSITOR AKTIENGESELLSCHAFT, OF BERLIN, GERMANY.

MATRIX-SETTING AND LINE-CASTING MACHINE.

Application filed February 8, 1924, Serial No. 691,528, and in Germany February 12, 1923.

This invention relates to matrix setting and line casting machines, in which rotating matrices and justifying spaces are taken from a magazine by using a keyboard, justified in lines, brought to a casting mold, cast and again distributed and placed in the magazine. In such machines, in order to increase their usefulness, it has become the rule to use the so-called two-letter matrices, 5 that is to say matrices which in place of one character, have two characters cut in the edge, one above the other, in such a manner that according to the position of the matrix relatively to the casting mold, the lower or 10 the higher character is cast, when casting the line. These machines must be provided with devices which allow, when collecting or forming the matrices into a line, of bringing them at will into the higher or lower position. 15 Such a device more particularly forms the subject of this invention.

The rectangular shape of the matrices with laterally projecting upper and lower lugs as generally used, may be assumed to 20 be known, also the collecting device. The latter is substantially constituted by a quickly travelling collecting band which, on the corresponding keys being depressed, brings the matrices dropping out from the 25 magazine, to the collecting point where they strike a quickly revolving star wheel which places them singly in upright position side by side and presses them to a point behind two small locking books. When two-letter 30 matrices are to be used, it has hitherto been usual to arrange the striking surfaces for the lower lugs of the matrices behind the collector wheel and adjustable in a vertical direction, or to arrange a second stop—the 35 so-called bridge—at a higher level and in such a manner that it may be pushed in and out. In that way the matrices may be collected at will in one of the two positions as regards their level.

40 The manipulation of the known constructions is however not very simple, more particularly as the progress of the line has to be watched with the greatest care. According to the invention, this is obviated by collecting all the matrices in one and the same position, namely in a mean or middle position, and by effecting the adjustment to "high" or "low" immediately on the completion of the setting of the given word, the 45 manipulation being purely mechanical, and the same for both positions.

A construction according to the invention is illustrated by way of example in the accompanying drawings, in which Figures 1 to 6 show the various positions of the switches or points and of the corresponding parts during the setting of a line from matrices which are partly to be in the "high" and partly in the "low" position, arranged as more particularly shown in Figure 7. 60 Figure 7 shows in a diagrammatic manner an arrangement of the setting of the matrices. Figures 1^a and 5^a are cross-sections respectively on the lines A—B and C—D of Figures 1 and 5. 70

The matrices are assembled in a known manner from a magazine by a collector band 1 (Figure 1) relative to a star wheel 2 which presses them behind locking books 3 against a stop 4 to engage in front of the assembled 75 matrices which is movable longitudinally and yieldingly urged in a direction toward the star wheel, and from which position they are delivered or advanced to a collecting conduit the side walls of which are arranged 80 with two pairs of parallel and predetermined spaced rails or ledges to arrange the conduit with opposite superposed or upper and lower recesses or channels for the engagement of the matrix lugs to support the 85 matrices. According to the present invention at a main position located between the upper and lower recesses of a lower pair of matrix lug engaging recesses at the entrance end of and in spaced relation to the conduit 90 recesses is arranged a matrix receiving support in the form of a rail or bar 5 on which the matrices delivered by the band 1 are positioned by the wheel 2. A switch in the form of the bar or rail 6 is pivotally supported at one end at the forward end of the bar 5, with the free end terminating adjacent the entrance end of the conduit recesses, 95 which switch is manually adjustable to direct or guide the matrices collected on the bar 5 and advanced from said bar to cause the matrix lugs to engage and be supported in either the upper or lower conduit recesses according to the position to which the switch is adjusted. A second matrix support in 100 the form of a pair of fixed and parallel bars are arranged above and spaced from the bar 5, switches 7 being pivotally supported at

105

the forward ends of said bars and normally yieldingly urged to position in alinement with the lower wall of the upper circuit recesses by springs 11 connected at one end to a fixed part and at the other end to levers 12 fixed to the switch support, said switches being adapted to be moved upward for the passage of matrix lugs into the upper recess when the switch 6 is adjusted to direct the matrices to position with the lower matrix lugs to engage in the upper recesses of the lower conduit recesses. The matrices are moved from the support 5 into the conduit by a finger 8 pivotally connected to a slide and engaging in the rear of the matrices assembled on the support 5 and as said slide is moved or advanced forward in the usual manner. The adjustment of the switch 6 is effected by a handle 10 which may be brought into either one of two positions, indicated by O, the upper position, and U, the lower position, said handle being in the nature of a yielding detent having a pin extending from the back to engage in either one of a pair of perforations arranged adjacent the indications O and U, and thus releasably retain the switch 6 in either one of its adjusted positions.

The operation is as follows: Let it be assumed that a line is to be set in which it is first desired that a number of matrices should be in the low position, followed by a number of matrices in the upper position and then again by a number in the low position. The first named matrices are marked I, the higher ones II, the matrices in low position following after these and situated at the farthest right hand side end are marked III (Figure 7). At the beginning of the operation the lever 10 is placed relative to the indication U (Figure 1) when the matrices I are released in the usual manner from the magazine and moved by the star wheel 2 on the bar 5. After a given number of matrices have been placed side by side, they are advanced to the left into the collecting conduit by the finger 8, the matrices sliding down and directed by the switch into the lower position (Figure 2). The lever 10 is then moved to O. The switch is thus raised (Figure 3), and the finger 8 is withdrawn or returned by the slide 9, the stop 4 pushes the line of matrices already set (that is to say the matrices which are to be in the low position) to the right. The matrix lugs during this movement of the matrices being directed by the switch 6 to position to engage below the support 5.

The mechanism is now in position for the addition of the part II of the line, that is to say all those matrices which in the finished line are to be in the upper position. Matrices are then assembled side by side in the usual manner (Figure 4) and then advanced to the left by the finger 8 and dur-

ing this movement slide upward on to and directed by the switch 6 so that the matrix lugs of the assembled matrices II will engage in the upper of the conduit recesses, the previously assembled matrices I and engaging below the bar 5 and switch 6 being directed so that the matrix lugs will engage in the lower conduit recesses. The forward movement of the matrices II will raise the switch 7 to permit of the passage thereunder of the upper matrix lugs, Figure 4. After the matrices pass the switch 7, said switch is again moved by the spring 11 to its normal position, and as retrograde movement is imparted to the finger 8 the matrices are again moved back to the right by the stop 4, the last set up matrices II during this movement being directed by the switch 7 so that the upper matrix lugs engage upon fixed bars extending in parallel and spaced relation to the bar 5 and in line with the switch 7 to be supported thereby. (Figures 6 and 7.)

The lever 10 is then again set on U, and the matrices for the line portion III are then assembled side by side upon the bar or rail 5 in the manner hereinbefore described, whereupon the process is repeated in exactly the same way as just described. After the line is finished, it is pushed off on to the casting carriage.

The present invention has the advantage that for each change in the matrix position, it requires merely a quick movement to and of the finger or collecting carriage 8, and a change of position of the switch 6. The manipulation is a purely mechanical one, and it is not necessary to watch the line.

If it is to be taken into consideration, that single matrices must be adapted to be subsequently removed from the copy for the purpose of correction, arrangements may be made which prevent the rest of the matrices from dropping out when the front of wall of the matrix conduit has been turned out, and a single matrix removed. Such arrangement does not however form part of the present invention.

What I claim is:

1. In matrix setting and line casting machines, a matrix collecting conduit having two pairs of parallel and predetermined spaced ledges on opposite walls to arrange the conduit with superposed matrix lug engaging recesses, a fixed matrix receiving support arranged at and spaced from the entrance ends of said conduit recesses, and a switch interposed between said fixed support and conduit recesses to direct the matrices advanced from said support into the conduit with the lugs thereon to engage either the upper or lower recesses in the collecting conduit.

2. In matrix setting and line casting machines, a matrix collecting conduit having superposed matrix lug engaging recesses, a

fixed matrix receiving and supporting bar arranged at and in spaced relation to the entrance end of said collecting conduit and positioned intermediate the recesses, means 5 to advance the matrices collected on said bar into the collecting conduit, and adjustable means interposed between said bar and the collecting conduit to direct the matrices advanced from the bar with the matrix lugs 10 to engage in either the upper or lower recesses in the collecting conduit.

3. In matrix setting and line casting machines, a matrix collecting conduit arranged with two pairs of superposed matrix lug 15 engaging recesses in the side walls, a fixed matrix receiving and supporting bar arranged at and in spaced relation to the entrance of said conduit and positioned intermediate the lower pair of recesses, a stop to 20 engage in front of the assembled matrices movable longitudinally of the conduit and yieldingly urged in a direction toward the bar, means to advance the matrices from the bar into the conduit, switch means interposed between said bar and the conduit to 25 direct the matrices to engage the lugs thereon into the lower or upper recesses as the matrices are advanced from the bar, said stop being adapted to return the matrices 30 to collecting position, and said switch means during said retrograde movement of the matrices adapted to guide the matrices with the lower matrix lugs to engage below the bar.

35 4. Matrix collecting means for matrix setting and line casting machines as claimed in claim 3, wherein a second pair of bars are superposed to the first bar for the engagement of the upper matrix lugs when the 40 matrices are returned to collecting position by the movable stop with the lower matrix lugs engaging above the matrix receiving and supporting bar to support the matrices from the upper lugs.

45 5. Matrix collecting means for matrix setting and line casting machines as claimed in claim 3, wherein a second pair of bars are superposed to the matrix receiving and supporting bar, and switches interposed between 50 said bars and conduit normally urged to position in line with the lower wall of the upper recess of the upper pair of recesses in the conduit and adapted to guide the matrices supported in the upper recesses in the 55 conduit to said superposed bars when retrograde movement is imparted to the matrices by the movable stop and the lower lugs of the previously set up matrices guided to engage above the matrix receiving and supporting bar to support subsequent set up 60 matrices by said upper bars from the upper matrix lugs, and said switches adapted to guide the matrices with the upper lugs to engage the upper conduit recesses when the

matrices are advanced from said upper bars. 65

6. In matrix collecting means for matrix setting and line casting machines, a collecting conduit arranged with two superposed pairs of matrix lug engaging recesses in the opposite walls thereof, a matrix receiving 70 support arranged at and spaced from the entrance end of the conduit, means to assemble matrices upon said support, matrix supporting means superposed to said receiving support, means to advance matrices assembled on said receiving support into the conduit, stop means to engage at the front of the assembled matrices movable longitudinally of the conduit yieldingly urged in a direction toward the support, a switch interposed between the matrix receiving support and conduit to direct the matrices advanced from said receiving support into the conduit with the matrix lugs to engage either the upper or lower conduit recesses, and direct 75 matrices advanced to the conduit with the matrix lugs engaging in the lower conduit recesses when retrograde movement is imparted thereto by the stop means to position with the matrix lugs to engage below 80 the matrix receiving support, and switch means interposed between the upper matrix supporting means and conduit operative to direct matrices which have been advanced to the conduit with the matrix lugs engaging 85 in the upper conduit recess to position with the upper matrix lugs to engage upon and be supported by the upper supporting means 90 when retrograde movement is imparted to said matrices by the stop means and direct 100 said matrices from said upper supporting means to position the matrices in the conduit with the upper matrix lugs engaging in the upper conduit recesses by any subsequent 105 advancing movement of the matrices.

7. In matrix setting and line casting machines, a matrix collecting conduit arranged with two pairs of parallelly arranged longitudinal recesses in the opposite walls thereof for the engagement of matrix lugs to support matrices in the conduit, a matrix receiving and supporting rail at and in spaced relation to the entrance end of the conduit and located in a mean position between the lower pair of conduit recesses, a switch bar 110 pivotally supported at the forward end of the matrix receiving and supporting rail with the free end to terminate adjacent the entrance end of the conduit recesses, and selective means to adjust said switch to direct 115 matrices assembled on and delivered from the rail with the matrix lugs to engage in either one of the conduit recesses.

In witness whereof I have hereunto set my hand.

Mrs. ANNA EMILIE EMMA PETRI-PALMEDO,
Executrix of the Estate of David Petri-Palmedo,
deceased.
